DESIGN FOR A TELEPHONE STAND

George A. Levis, Williamsport, Pa.

Application September 22, 1947, Serial No. 141,534

Term of patent 14 years

(Cl. D26—14)

To all whom it may concern:

Be it known that I, George A. Levis, a citizen of the United States, residing in the city of Williamsport, county of Lycoming, State of Pennsylvania, have invented a new, original, and ornamental Design for Telephone Stands, of which the following is a specification, reference being had to the accompanying drawing, forming part thereof, and in which

I claim:

The ornamental design for a telephone stand, as shown.

GEORGE A. LEVIS.
